MACHINE GUN MECHANISM

William Daniel Douglas Hammond, Los Angeles,
Calif., assignor to Machinery Sales Company,
Los Angeles, Calif., a corporation of California

Application August 11, 1941, Serial No. 406,249

3 Claims. (Cl. 42—3)

The machine gun of this invention relates to that division of machine guns generally known as sub-machine guns, and has for its purpose the following provisions, to wit:

- (1st) Extreme simplicity.
- (2nd) Low cost of manufacture.
- (3rd) A minimum of working parts.
- (4th) Reliability of operation.
- (5th) Lightness of weight.
- (6th) Maneuverability when firing.
- (7th) Portability.
- (8th) Ease of repair, and/or parts replacement.
- (9th) To provide a firing mechanism for machine guns in which pressures alternately applicable at points tangential to the place of fulcrum in a hammer are adapted to periodically raise the hammer and snap the same upon a firing pin.
- (10th) To provide means in a firing mechanism for a gun to cock the hammer whereby the bolt is able to move in recoil to effect reloading of the gun, and cam means actuated by return or breech closing movement of the bolt to swing the hammer past a point of off-center and through a point of dead-center spring-thrust pressure whereby said spring-thrust pressure forces the hammer upwardly in an ascending movement following the preceding movement of the bolt so that the firing pin is struck just subsequent to the closing of the breech by the said bolt.

(11th) To provide a firing mechanism in a machine gun wherein a hammer is provided with a spring, the thrust of which in extreme positions is applicable in directions tangential to the fulcrum of the hammer, the hammer being alternately compressible by the bolt of the gun in recoil and being ascendingly motivated by, (a) bolt actuated pressure, followed by, (b) thrust of the said spring in one of the directions tangential of the fulcrum of the hammer whereby the hammer is alternately moved to and from firing position.

(12th) To provide a firing mechanism for a machine gun, wherein the hammer of the gun is compressible by recoil movement of the bolt of the gun, and which hammer is actuated to firing position by the forces in combination, of bolt actuated means, and, in sequence, spring-thrust pressure means, whereby the hammer is repetitiously moved to and from firing position.

Other objects, features and advantages of the invention may appear from the accompanying drawings, the specification, and subjoined claims.

In the drawings:

Figure 1 is a schematic view showing the operating elements involved in the firing mechanism

of this invention, the parts being shown in firing position.

Figure 2 is a view of the invention showing the operating parts in recoil position.

5 Figure 3 is a view of the functional elements of the invention in an intermediate position moving toward firing position.

Figure 4 is a view in section taken along line 4—4 of Fig. 1 showing the hammer in raised position and other associated elements of the gun 10 in co-operative position.

Figure 5 is a view in section taken along line 5—5 of Fig. 2 showing the bolt actuated cam in position accommodating the depressed hammer, the reversal of this position is adapted to initially 15 start the hammer in its ascending movement toward striking the firing pin.

Figure 6 is a sectional view taken substantially along line 6—6, in Figure 4 showing in particular 20 the means used to shield the trigger actuated bar within the body portion of the gun, the bar being the means used to connect the trigger with the hammer releasing block.

Figure 7 is a side elevation of a portion of the 25 gun body, the view being adapted to show that one of the faces of the body of the gun is detachable, being held in position by any practical means such as screws.

The present invention is concerned only with 30 the mechanical elements necessary to obtain repetitive movement of the hammer to and from position necessary to detonate a cartridge. Such accessories as grips and sheathing for the gun have been entirely eliminated as well as the customary means to automatically load cartridges 35 from a clip or drum, for such adjuncts are within the scope of the accepted art and are in reality, irrelevant to the present invention, and accordingly have not been illustrated.

40 In the drawings the reference character 10 indicates a body or case within which the several operating elements of the gun are functional.

Within the body 10, I place a breech bolt 12 which I recess as shown at 14 to receive a hammer 16 in its necessary movement to and from 45 firing pin striking position.

A firing pin 18 is centrally aligned within the bolt 12, being provided with a spring 20 which, bearing against a head 22 upon the firing pin and 50 against the end wall 24 of a recess within which the head is movable, is adapted to normally urge the firing pin head into the chamfered portion 14 whereby the firing pin may be actuated by the hammer 16 as will more fully appear as the specification is developed. A pin 26 secured within

the bolt and having a free end loosely fitted within a slot 28 in the pin 18 is adapted to limit movement of the firing pin in extreme directions, while a spring 30 within the body 10 and encircling an extension 12a of the bolt 12, is adapted to not only absorb recoil movement of the bolt but to also force return of the bolt to breech closing position, which movement also forces a cartridge 32 from a clip 34 into the firing chamber 36 of the gun.

The body portion 10 is provided or formed with a downwardly extending rectangular pocket 38 having one open side which is coverable with a detachable plate 40 as shown in Figure 7. The hammer 16 is fulcrumed within this pocket although, as shown in Figures 1, 2, and 4, it swings upon its fulcrum 42 in such manner as to partially occupy both the pocket and the recess 14 when swung into functioning position. The width of the recess 14 and the width of the pocket 38 are equal as shown in Figures 4 and 5, and the hammer 16 is of such width as to closely fit and move therein. The head of the hammer is of course of solid metal while the end A thereof is bifurcated, being formed with parallel legs 44 and 46. A wrist pin 48 extends across the space between the legs 44 and 46 and is suitably connected in a substantially integral manner with a pin 50 the opposite end of which is movable in a tubular member 55 secured upon a second wrist pin 48a, which is journalled in the wall 52 of the pocket 38 and in the cover plate 40. A spring 53 surrounds pin 50 and tubular member 55, being under compression to force the wrist pin 48 upwardly. When the hammer is in depressed or cocked position the line of action of this spring passes close to the axis of hammer pivot 42; in the full cocked position of Fig. 2 passing slightly to the left of the pivot, and in the latching position of Fig. 3 passing slightly to the right of the pivot.

A cam 54, freely movable upon a pin 56 positioned within the pocket 38, is adapted to be in intermittent contact with the edge portions 58 of the legs 44 and 46 along the face 60 of the cam 54, while the opposite extreme thereof is formed with a lobe 62 which is adapted to be intermittently in striking contact with the end 64 of a slot 66 formed in the under-side of the bolt 12. The opposite end of the slot 66 is sealed from open connection with the breech by the end wall 68. Intermediate portions of the cam 54 are formed in a constant radius whereby the cam may partially rotate within the slot 66, while a pin 70 secured in the wall portions 40 and 52, and extending through an arcuate slot 72 in the cam, is adapted to form a stop limit of rotation in the cam.

A trigger 74, fulcrumed at 76 and having an extension 78, is connected with a bar 80 by means of a slot and pin arrangement 82. As shown in Figure 6, the pin 84 extends laterally of the trigger and is integrally connected with the bar 80 which lies within an elongated slot 86 formed in the wall 52 of the pocket 38. The opposite end of the bar 80 is integrally connected to a block or sear 88 of such width as to be snugly fitted within and movable within the space defined by the walls 52 and 40. A pin 90, secured to the block 88 and extending through the wall 92, is adapted to center a spring 94 which in resisting compression naturally tends to throw the trigger 74 into non-functional position.

The preceding description is believed to cover the physical detail involved in the structural ar-

rangement involved in the invention, co-relation of the several elements therein and a description of operation will now be made.

It will be assumed that the gun has been fired and that the relationship between the hammer 16, the bolt 12, the cam 54, and particularly including the pin and sleeve elements 50 and 55 respectively, and the spring 53, are in the position shown in Figure 1. Movement of the bolt in recoil will cause the bolt surface 13 to bear against the hammer 16 so that the hammer will progressively swing upon its fulcrum 42 until it is positioned as shown in Figure 2, the surface 65 of the bolt having slid over the surface 17 of the hammer. It is to be noted at this point that the degree of resistance offered by the hammer to movement is not alone proportional to resistance offered by the spring 53 to compression, but is more particularly determined by distance between the point of contact between the heel or corner 65a of the bolt and the axial center of the fulcrum point 42.

The point of application of bolt pressure upon the hammer is to be considered relatively important for the resistance thus developed to movement of the hammer affords in a large measure the degree of lock in the hammer against idle movement.

Movement of the bolt to full recoil position leaves the cam face 60 in full contact with the edges 58 of the legs 44 and 46 of the hammer, throwing the cam into upper-most position so that the lobe 62 is aligned in a rear-ward direction as shown in Figure 2. Upon absorption of pressure of the bolt in recoil, the spring 30 forces the bolt to retrace its movement and in so doing the face 64 strikes the lobe 62 and partially rotating the cam causes the hammer to be moved in a reverse direction. The block as shown in Figure 3, being in trigger pressed advanced position, permits free movement of the hammer and full automatic firing of the gun for the reason that the cam has imparted initial motion to the hammer and has forced the spring pressure point 48 through the line B-C so that the thrust of the previously compressed spring 53 is free to carry the hammer 16 upwardly through its range of travel to strike the firing pin 18. If the trigger is released the sear 88 will be drawn under the extensions 44 and 46 of the hammer (Fig. 6) and the latter will be retained in the locking position of Fig. 3. The first or initial movement in the hammer is obtained as aforesaid, by reason of bolt actuated cam pressure upon the legs thereof, concurrently with having moved from pressure contact with the hammer proper, and this movement is of sufficient magnitude to carry the point of fulcrum 48 past the medial vertical line indicated by the reference characters B and C, which line is co-incidental with the fulcrum 42 and 48a, so that thereafter, thrust afforded by compression of the spring 53 reacts to throw the hammer upwardly through the remainder of its course of travel.

In like manner, during movement of the bolt in recoil, after the hammer has been forced by recoil pressure past the center line B-C, the line of spring pressure thrust, switches from the line E-F, to the line G-H, so that after a measure of movement due to recoil of the gun, the remainder of the retractive movement of the hammer is effected by pressure of the spring 53, thus limiting friction and wear to a minimum as well as affording a well balanced movement in those elements of the gun which move to and from

functional position and which by their nature must be relatively heavy and as a consequence possess a considerable degree of inertia.

The preceding matter is descriptive of a cycle of operation of the mechanism of this invention, like or repetitious movement would naturally require repetitious description.

In conclusion it may be stated that various changes and modifications may be made in practicing the invention in departure from the drawings and description as given, without however, departing from the spirit of the invention as defined by the appended claims, which are accordingly to be considered as definitive of the invention.

I claim:

1. A firearm comprising reciprocable breech closing mechanism, a firing pin, a hammer pivoted in position to engage the firing pin when the breech is closed, a hammer spring mechanism having pivotal connection with the hammer with the line of action of the spring passing close to the pivot of the hammer when the latter is in cocked position, a sear adapted to retain the hammer in cocked position with the line of action of the hammer spring passing to that side of the hammer pivot in which the spring tends to move the hammer to firing position, a trigger operative upon pressure to shift the sear, connections between the breech closing mechanism and the hammer operative upon opening of the breech to move the hammer a substantial amount beyond said cocked position, and mechanism actuated by the breech closing mechanism upon closure of the breech to cause the hammer spring to shift the hammer into cocked position to engage the sear if the trigger is not pressed, or to continue rotation into firing position under the action of the hammer spring if the trigger is kept pressed.

2. A firearm comprising a reciprocable breech closing mechanism, a firing pin, a hammer pivoted in position to engage the firing pin when the breech is closed, a hammer spring mechanism having pivotal connection with the hammer with the line of action of the spring passing close to the pivot of the hammer when the latter is in cocked position, connections between the breech closing mechanism and the hammer operative upon opening of the breech to move the hammer into a position in which the line of action of the

hammer spring will pass to that side of the hammer pivot in which the spring tends to move the hammer away from firing position, whereby said spring will temporarily hold the hammer in over-cocked position, mechanism actuated by the breech closing mechanism upon closure of the breech to shift the hammer in a direction to cause the line of action of the hammer spring to shift to that side of the hammer pivot in which the spring tends to move the hammer into firing position, a sear adapted to retain the hammer in cocked position when so shifted by the last-named mechanism, and a trigger operative upon pressure to shift the sear to release the hammer.

3. A firearm comprising a reciprocable breech closing mechanism, a firing pin, a hammer pivoted in position to engage the firing pin when the breech is closed and having a striking surface and a portion extending on the opposite side of the pivot from the striking surface, a hammer spring mechanism having pivotal connection with the hammer with the line of action of the spring passing close to the pivot of the hammer when the latter is in cocked position, connections between the breech closing mechanism and the hammer operative upon opening of the breech to move the hammer into a full-cocked position in which the line of action of the hammer spring will pass to that side of the hammer pivot in which the spring tends to move the hammer away from firing position whereby said spring will temporarily hold the hammer in over-cocked position, a cam rotatably mounted in adjacency both to the breech closing mechanism and to the hammer, said cam having a surface engaging the extending portion of the hammer when the latter is in full cocked position and a second surface extending into engagement with the breech closing mechanism, an abutment on the breech closing mechanism operable on closure of the breech to engage and rotate said cam and thereby to cause rotation of the hammer into a latched position in which the line of action of the hammer spring is on that side of the hammer pivot in which the spring tends to move the hammer into firing position, a sear spring-pressed into position to hold the hammer extension in said latched position, and a trigger operative upon pressure to shift the sear to release the hammer.

50 WILLIAM DANIEL DOUGLAS HAMMOND.
